METHOD AND MEANS FOR REFLUTING TEXTILE ROLLS

Application filed March 28, 1931. Serial No. 526,090.

This invention relates to a method and means of re-fluting textile rolls and the like so as to provide said rolls with new flutes and place them in as good, or better, condition as when new.

An object of this invention is to provide means for rendering textile rolls, which have become worn, capable of use by re-fluting the same and re-allocating the surface thereof 10 and building up the flutes again to their original condition.

Another object of this invention is to provide a method and means of re-fluting all 15 types of textile rolls by imparting to the surface thereof flutes in all respect, as good as, if not better, than the original surface when the rolls were new.

It is well known that fluted rolls, when 20 they become worn, cannot be re-fluted by merely passing a file or stationary cutter along the old grooves, as this will produce a roll of less cross-sectional area than a new roll. This invention, by employing a revoluble cutting tool, does not remove any portion of the 25 metal from the roll, but displaces the same and forces it radially outward and builds up the flutes to their original cross-sectional area, providing rolls equally as good as new.

The rolling and cutting members for 30 reforming the flutes are chosen to fit the particular shape of the old groove in any particular roll, and in many instances, these rolling and cutting members must be ground to the proper shape so as to be suitable for a particular groove in a particular type of textile roll so as to fit the groove in such a manner as to reform the flute without breaking the metal. Also it might be noted that another 35 advantage of the method and means herein employed, is that it is a cold rolled process so that low places in a portion of the old rolls will be built up to a thickness corresponding to the remaining portion of the roll for the reason that a certain amount of the metal is 40 pushed longitudinally of the roll a short distance by the rolling and cutting tools while at the same time being pressed laterally and seeking a place in which to be deposited, and 45 in this manner a flute having a smooth sidewall is provided which is free from burrs to

a much greater extent than are the grooves formed by filing or cutting by means of a stationary cutting tool. Also it is well known that by building flutes in this manner that the molecules are packed together forming a flute 55 which is more resistant to wear than one which is formed by cutting by a file or a stationary cutter. Thus, it is seen by the method employed that a roll may be re-fluted and put in a better condition than a new roll. 60

By means of this process, a smoother flute is provided which causes the yarn or other fiber passing between the rolls to clear the rolls much better than if new rolls made by filing or cutting the flutes with a stationary 65 cutter were used. One method heretofore employed in cutting grooves has been a positively driven rotary cutter which acts in a manner as above described but leaving a rough surface to the sidewalls of the flutes. 70

Some of the objects of the invention having been stated, other objects will appear as the description proceeds when taken in connection with the accompanying drawings, in which— 75

Figure 1 is a side elevation of one form of the mechanism which may be used in re-fluting the rolls;

Figure 2 is a plan view of Figure 1;

Figure 3 is a transverse cross-sectional 80 view taken along the line 3—3 in Figure 2;

Figure 4 is a cross-sectional view taken through the cutting tool;

Figure 5 is an elevation of two bosses on a drawing roll showing one before the operation of refluting and the other after it has been re-fluted; 85

Figure 6 is a cross-sectional view taken along the line 6—6 in Figure 5;

Figure 7 is a cross-sectional view taken 90 along the line 7—7 in Figure 5.

Referring more particularly to the drawings, the numerals 10 and 11 indicate suitable supports for a table 9 which has members 12 and 13 secured thereon, said members 12 and 13 having upstanding end portions 14 and 15 and the central stud supporting portions 16 and 17 which have studs 18 and 19 therein on which are pivotally mounted arms 20 and 21 which are joined together 95 100

by means of a rod 22 being secured by means of stud bolts 23 and 24, and the other end of said members 20 and 21 have secured therein a square rod 25 by means of stud bolts 26 and 27, and on this rod 25 are adjustably mounted holding members 28 and 29, each of which have a V-shaped notch 30 in the upper end thereof, said members 28 and 29 being adjustably secured on said rod 25 by means of bolts 31, said members 28 and 29 having suitable bearings 33 therein, and the V-shaped notches 30 are adapted to support a textile roll 36 for being operated upon.

In the portions 14 and 15 of supports 12 and 13 is mounted a square rod 37 which serves as a slide for a cutting tool mechanism. This slide 37 is held in position by means of stud bolts 39 and 40, and on this slide, a member 42 is slidably mounted by having a suitable bearing portion 43, said member 42 being a split member held in position by means of bolts 44, and one portion of member 42 projects downwardly as at 45 and has secured thereto cutting tool 46, said cutting tool having a plurality of threaded holes 47 therein which are adapted to be engaged by stud bolts 48 slidably penetrating holes in the portion 45 of member 42. This member 46 projects laterally and has an elongated slot 50 therein in which a plurality of rolling and cutting wheels 51 are rotatably mounted on pins 52 which are fixedly secured in the lower portion of member 46 and span the slots 50. These rolling and cutting disks 51 are similar to pipe cutting disks and are adapted to follow the old flutes in the roll for building the same up to their original condition. The disks 51 may vary in size and if desired, the central ones may be slightly larger than the end ones.

Member 42 has secured therein a stud bolt 55 on which is loosely mounted bearing portion 56 of connecting rod 57, said connecting rod 57 being adjustably mounted in a slot 58 by means of bolt 59 to adjust the length of stroke of the cutting tool, said slot 58 being in one of the spokes of wheel 60 which wheel is fixedly secured on a shaft 61 which shaft 50 is mounted in bearings 62 and 63 in supports 64, and on the other end of said shaft a drive pulley 66 is fixedly secured having a belt 67 connected to any suitable source of power for driving the same.

Spanning the distance between the supports 10 and 11 is a rod 70 on which is pivotally mounted a lever 71 having a plurality of holes 72 therein in which the lower end of a rod 73 may be adjustably mounted, and the upper end of this rod 73 is pivotally secured to rod 22 for lowering one end of members 20 and 21 and pressing the roll 36 in the path of the cutting tool. Secured to table 9 is a member 75 in which is secured a support 76 which projects laterally over rod 22 and has

an eye bolt 77 secured therein to which is secured a tension spring 78, the lower end of said tension spring being secured to rod 22, the purpose being to normally hold the roll holding end of members 20 and 21 away from the path of the cutting tool.

Member 71 has a pedal portion 79 on which the foot of the operator is adapted to be placed for controlling the position of roll 36.

In operation, a roll 36 is placed in the mechanism and the member 71 is depressed which throws the roll in the path of the cutting wheels 51, and the cutting tool slides back and forth on slide 37 and follows the old grooves 80 in the roll.

In Figure 6 it is seen that the grooves 80 are shallow, as the tips of the flutes have been worn down and an elevation of this is shown in the left-hand end of Figure 5. The passing of the cutting wheels along the grooves 80 re-allocates the molecules and builds up the rolls to the position shown at the right hand end of Figure 5, or shown in cross-section in Figure 7. This does not remove any of the metal from the roll but re-allocates the metal and builds up the flutes by pressing the molecules outwardly and upwardly and builds the roll to its original condition and making the cross-section of the roll slightly larger if desired, than its original condition, and then a suitable dressing operation such as emery cloth and the like is performed on the roll, leaving the tips of the flutes slightly dulled to provide a roll equivalent in all respects to a new roll.

It is desired to be pointed out that this operation is quite unlike the method of filing or cutting new grooves, but on the contrary, this method and means retains all of the metal of the roll and re-allocates the molecules and builds up the rolls by providing flutes on the same of the same cross-sectional area as a new roll.

In the drawings and specification, there has been set forth a preferred embodiment of the invention and although specific terms are employed, they are used in a generic and descriptive sense only and not for purposes of limitation, the scope of the invention being set forth in the appended claims.

We claim:

1. A machine for reforming flutes on a worn textile roll which comprises means for holding a roll, a reciprocating tool member, a plurality of rolling and cutting tools in said tool member mounted in alinement one behind the other, means for holding said roll in engagement with said rolling and cutting tools, and means for reciprocating said tool member back and forth a plurality of times for each groove reformed.

2. In a machine for refuting textile rolls having a suitable support and a pivoted work holding device mounted on said support and a slide fixed on said support, a cutting tool

mounted for reciprocation on said slide, means for imparting reciprocation to said cutting tool, said cutting tool comprising a plurality of rotatable cutting and displacing members, and means for holding a roll in the path of said reciprocating cutting tool.

5. That method of refluting a worn textile roll to restore it to its original size which comprises causing a plurality of rolling and cutting members to traverse each worn groove back and forth a plurality of times while pressing against the roll to displace the metal and build up the flutes.

10. That method of forming new flutes on a worn textile roll which comprises subjecting each worn groove to the action of a plurality of rolling and cutting members following one behind the other and traversing the groove back and forth a plurality of times while being pressed against the roll and then 15 subjecting each succeeding groove in the roll to the above described action.

15. That process of forming new flutes on worn textile rolls which comprises providing a plurality of rolling cutting members disposed in alinement one behind the other, causing said rolling and cutting members to move back and forth in the old grooves in the textile roll a plurality of times while the 20 rolling and cutting members are under pressure to displace the metal in the roll to form new flutes projecting radially outward farther than the old flutes.

25. That method of rolling a worn textile roll to rebuild its flutes to their original dimensions which comprises passing, while under pressure, a plurality of longitudinally aligned rolling and cutting members back and forth along one groove and continuing this 30 operation on the succeeding grooves until all grooves are traversed a plurality of times by said rolling and cutting members.

In testimony whereof we affix our signatures.
